Primary Examiner — Angela Lee(74) *Attorney, Agent, or Firm* — Robert A. Blaha; Smith Risley Tempel Santos LLC(57) **CLAIM**

The ornamental design for an animated graphical user interface for a portion of a display screen, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever. FIG. 1 is a first image in the sequence for an animated graphical user interface for a portion of a display screen showing our new design.

FIG. 2 is the second image thereof;
FIG. 3 is the third image thereof;
FIG. 4 is the fourth image thereof;
FIG. 5 is the fifth image thereof;
FIG. 6 is the sixth image thereof;
FIG. 7 is the seventh image thereof; and,
FIG. 8 is the eighth image thereof.

The appearance of the animated graphical user interface sequentially transitions between the images shown in FIGS. 1-8. No ornamental aspects are associated with the process or period in which one image transitions to another image. The portions of the graphical user interface and display screen shown in broken lines are included for the purpose of illustrating environment and form no part of the claimed design.
